UNITED STATES PATENT OFFICE

2,223,317

WEAVING MACHINE

Walkley B. Ewing, Grand Rapids, Mich., assignor
to Ewing Development Company, Bay City,
Mich., a corporation of Michigan

Application November 7, 1938, Serial No. 239,240

41 Claims. (Cl. 140—3)

This invention relates to a new method of weaving metal fabric and particularly to a machine for weaving metal fabric in accordance with my new method.

5 My new method of weaving is an improvement over that contemplated in producing the metal cloth disclosed in Grebe Patent No. 2,078,940 wherein filler ribbons or wires of elongated cross-section are woven in crosswise of the cloth by an
0 over and under weave of longitudinally extending pairs of warp wires, the filler ribbons or strands of elongated cross-section being positioned with their long sides at an angle to the plane of the cloth. In fabricating metal cloth
5 in accordance with the teaching of the Grebe patent, it has been observed that the resulting material upon being subjected to the common stresses and the resultant distortion does not always return to its normal shape. More specifically, I have found that relative movement occurs between the warp wires of the pairs of warp wires in the area where these wires cross each other. This area is located between adjacent filler ribbons or wires. I have discovered that
0 in this type of metal fabric the warp wires must be locked or fastened together against relative movement in this vital area if a fabric is to be produced having the requisite properties for universal acceptance.
0 It is an object of this invention to provide a method of weaving a metal fabric or cloth composed of a plurality of warp strands extending lengthwise of the cloth and a plurality of filler ribbons or strands of elongated cross-section extending across the fabric with the long sides thereof substantially parallel and disposed at an angle to the plane of the cloth by virtue of which method of weaving a cloth results that will withstand the common forces to which it is subjected without becoming distorted beyond return of its constituent elements to their normal relative positions. More specifically it is an object to provide a method of weaving the instant type of cloth that will result in fastening together the warp wires of the respective pairs in the area of their crossing between successive filler ribbons or strands of elongated cross-section, whereby to impart to the cloth the requisite qualities above enumerated and thus render
0 it more useful in such broad applications as in the insect screen field, in the field of shading devices, and in the gas and liquid contact field as well as in equivalent relations.

It is an object of this invention to provide
5 a weaving machine for producing metal cloth

of any desired size of mesh in accordance with my improved method.

It is a further object to provide a machine of this type that is capable of weaving a plurality of pieces of cloth simultaneously. 5

A still further and more specific object is to provide a weaving machine particularly adapted to weave fine mesh fabric of the present type possessing the above desired properties.

A more specific object of this invention is to 10 provide in a weaving machine of the present class, a new arrangement of weaving head, warp wire supply means and filler wire supply means having a new mode of coaction.

It is a still further object to provide in a weaving machine of the present class, a novel arrangement of elements defining a comb assembly and operating means therefor including a new mode of coaction between these elements.

It is a further and more specific object to 20 provide in a weaving machine of the present class, a comb and quill assembly having a new and improved mode of coaction whereby ribbon elements or filler strands of elongated cross-section may be woven in at any desired angle to 25 the plane of the cloth.

A still more specific object is the provision of a new and improved quill and rack assembly whereby the respective quills are rotated simultaneously in a continuous direction at successive 30 intervals to produce a symmetrical line of twists without releasing driving contact between the rack and the quills.

Another specific object is the provision in a weaving machine for weaving fine mesh fabric of 35 an improved quill for feeding a pair of warp wires off the nose thereof constructed particularly with reference to the problem of forming as large a shed as possible for the reception of a side injected ribbon or filler strand of elongated cross-section. 40

Included among the special objects of this invention is the provision of an improved arrangement for supplying warp wires to the quills whereby to prevent the twisting together of warp wires behind their respective quills while at the same time subjecting the warp wires to a slight feeding tension. More specifically it is an object to provide a special arrangement of conduits for maintaining the warp wires separated and for 45 leading the same from their respective supply spools to the rear of their respective quills. Again more specifically, it is an object to provide a special arrangement of turntables and warp supply spools mounted thereon whereby to de- 50 55

liver the warp wires through the conduits to the quills without twisting the warp wires together at the rear of the quills, notwithstanding the rotation of the quills for twisting the wires of each 5 pair together adjacent the forward end thereof in locking a filler strip in place.

The above and other objects, advantages and uses of my invention will become more apparent from a reading of the following specification 10 and claims taken in connection with the appended drawings which form a part of this specification and wherein:

Fig. 1 is a plan view showing schematically the entire machine arranged in accordance with 15 a preferred embodiment of my invention and indicating the relationship of the weaving head, warp wire supply, and rolling mill supply;

Fig. 2 is a front elevation of the weaving head and rolling mill;

20 Fig. 3 is a right side elevation of the weaving head of Fig. 2 and showing in addition, the centralizing panel together with the forward one of the warp wire spool mounting panels;

Fig. 4 is a section taken substantially on the 25 line 4—4 of Fig. 2 and showing the comb assembly together with its support adjusted for weaving 10° material;

Fig. 5 is an enlarged view of the comb and quill 30 assembly of Fig. 4, bringing out to advantage the proper positioning of the comb assembly relative to the quill noses in order to satisfy the controlling conditions necessary in effecting a firm tie when weaving angle material;

Fig. 6 is a view in perspective showing a piece 35 of material woven by my machine;

Fig. 7 is a section substantially on line 7—7 of Fig. 2 showing the rack operating cam and associated mechanism, the comb assembly in this 40 figure being shown in the vertical plane which position it will occupy when weaving right angle material;

Fig. 8 is a section substantially on the line 8—8 of Figs. 2 and 9 showing the comb raising and 45 lowering cam and lever mechanism, the comb assembly as in Fig. 7 being shown in position for weaving right angle material;

Fig. 9 is a broken-away plan view taken substantially on line 9—9 of Fig. 8 and showing the 50 relationship between the comb raising and lowering lever and cam mechanism, and the comb assembly forward and backward shifting arm and cam mechanism;

Fig. 10 is an enlarged broken-away elevation 55 substantially on the line 10—10 of Fig. 12 showing the comb assembly including the comb proper; the backplate; and the geared quills; innerlying parts being broken away in succession from left to right for the purpose of showing to advantage the interior construction;

60 Fig. 11 is a section taken substantially on the line 11—11 of Fig. 10 and showing the arrangement of the comb assembly; the quills; and the warp wire thereon together with tensioning means therefor; the comb assembly being shown adjusted for right angle material as in Fig. 7;

Fig. 12 is a plan view in section substantially 70 on the line 12—12 of Fig. 10 and showing the relationship of the wedge-shaped quill noses to the backplate of the comb assembly; the manner of curving the discharge guides on the forward end of the quills; the relationship of the driving rack to the staggered overlapping quill gears; and the arrangement of tensioning means on the rear end of the quills;

75 Figs. 13a and 13b show a vertical section indi-

cated generally at 13—13 on Fig. 1 showing the arrangement of the conduit guide means for conducting the warp wires from the centralizing panel to the rear ends of the quills.

Fig. 14 is a section on line 14—14 of Fig. 13, 5 showing the relationship of the warp wire guides; tensioning means for the warp wires; and the connection of the universal joint forming wires to the rear ends of the quills;

Fig. 15 is a section on line 15—15 of Fig. 13, 10 showing the arrangement of outer and inner conduits together with the manner of connecting the rear ends of the universal joint forming wires to these conduits;

Fig. 16 is a section taken on line 16—16 of Fig. 15 13;

Fig. 17 is a section taken on line 17—17 of Fig. 13;

Fig. 18 is a partial vertical section indicated at 18—18 of Fig. 1, showing the warp wire spool 20 and supporting table arrangement together with the drive therefor;

Fig. 19 is a plan view in section on the line 19—19 of Fig. 18;

Fig. 20 is a rear elevation of the structure shown 25 in Fig. 18;

Fig. 21 is a section on line 21—21 of Fig. 19, showing the arrangement for quick removal and replacement of the spools;

Fig. 22 is a section on line 22—22 of Fig. 18 30 showing the brake arrangement for the spools;

Fig. 23 is a plan view of the mill showing the stationary spools of round wire for supplying the flattening rolls and also showing a portion of the 35 cooperating end of the comb assembly including the guide channel together with the cutoff knife for cutting off the flat wires adjacent the side of the comb assembly;

Fig. 24 is a schematic elevation partly in section showing the stationary spool of round wire 40 with the wire being fed from the side thereof to the flattening rolls;

Fig. 25 is a side elevation of the rolling mill partially in section and including a showing of the fluid motor for moving the reciprocating rack 45 for operating the rolls; the control means thereof; and the special adjustable features of the mill;

Fig. 26 is a front elevation partly in vertical section substantially on the line 26—26 of Fig. 25;

Fig. 27 is an enlarged broken-away sectional view substantially on line 27—27 of Fig. 26 showing the knife cut-off structure;

Figs. 28a through 32f are schematic views illustrating the successive relative positions of the 55 parts of my machine in carrying out a complete weaving cycle; and

Figs. 33a and 33b show the composite timing chart of my machine.

Turning to the drawings wherein there is illustrated a preferred embodiment of a weaving 60 machine in accordance with my invention, there is shown in Fig. 1 a weaving head assembly indicated generally at A; a warp wire supply assembly indicated generally at B; and a filler wire forming an injecting assembly indicated generally at C.

The weaving head A comprises essentially a comb assembly indicated generally at 10 (see Figs. 4 to 12) formed with a plurality of guideways 11 (see Fig. 10) for guidably receiving filler strands 13 of elongated cross-section crosswise of a corresponding number of pieces of cloth being simultaneously woven and for holding the same with their major surfaces disposed at a predetermined angle to the planes of the respective pieces of 75

cloth. The comb assembly is further specially formed adjacent the guide and holding means 11 for cooperation with two superimposed rows of rotatable quills referred to generally at 15 and 16 (Figs. 5, 10, 11 and 12), the function of which is to feed a plurality of uniformly spaced pairs of warp wires 17 about the filler strands 13 and to twist the respective warp wires of each pair of warp wires together to form interlocking twists 19 (Figs. 6, 11 and 28 to 31) for securely fastening the filler strands in position in their respective fabrics. The guide and holding means 11 is further arranged to be subsequently opened for advancing and releasing the filler strands preparatory to again being moved to a position therebehind for receiving additional filler strands 13 in said guides for likewise being tied into the cloth by again rotating the quills 15 and 16. Power means is provided in the form of motor driven cams and levers (see Figs. 4 to 9) for effecting the operation of the weaving head assembly in the proper sequence. While I have shown the weaving head as having two guides 11 together with corresponding rows of quills for weaving two pieces of cloth simultaneously, this is merely for illustration and it will be apparent that a larger number of pieces of cloth may be simultaneously woven, by merely providing additional guides 11 and corresponding rows of geared quills 16. On the other hand, only one piece of fabric may be woven, employing only one guide and one row of quills.

Warp wire supply assembly B comprises generally a plurality of rotatable tables 21 (Figs. 3, 35 and 18 to 21) corresponding in number to the number of quills, each table supporting a pair of spools 22 and 23 for supplying pairs of warp wires 17 to each of said quills, these tables being driven the same total number of revolutions as the quills by motor 24 (Fig. 1) through reduction gearing 25 and chain 26 whereby to prevent the twisting together of the warp wires behind the quills. The warp wires pass from adjacent their respective spools through a special arrangement 45 of conduits 27 (Figs. 1 and 13 through 17) for preventing entanglement and for imparting a slight tension to the warp wires.

The filler wire forming and injecting mill assembly C (see Figs. 1 and 23 to 27) comprises generally a pair of tangential flattening or elongating rolls 28 and 29 driven periodically in sequence with the weaving head assembly operation by a hydraulic motor 30. These rolls receive a pair of round wires from stationary spools 32 and 33 and flatten the same to form wires 13 of elongated cross-section and simultaneously inject these wires into the guide and holding means 11 of the comb assembly above described. This wire is cut off adjacent the side of the cloth in response to the forward movement of the comb assembly, during the subsequent advance of cloth, by knife 34 carried by the weaving head A and operating in conjunction with stationary shearing block 35, mounted on the mill frame (Figs. 26 and 27).

While I prefer this arrangement for cutting off the filler wire since it has a number of distinct advantages, I nevertheless contemplate the use of other well known cutting means as coming within the broad scope of my invention, when employed in the combination disclosed.

Weaving head assembly

Referring now in greater detail to the drawings 75 the comb assembly portion of the weaving head

indicated generally at 10 comprises a back plate 50, (Figs. 10 to 12) formed with a plurality of vertical slots 51 therethrough for the passage of pairs of warp wires 17; a pair of channels 52 traversing the forward face thereof and intersecting vertical slots 51 and of the proper size for guidably receiving the ribbon-like filler strands 13; and a vertically reciprocable comb 54 formed with teeth 55 defining slots 56 therebetween corresponding in position to slots 51 in back plate 50. 10 This comb 54 is operable on the face of plate 50 from a position wherein the teeth 55 thereof extend up between the adjacent pairs of warp wires 17 and in which position these teeth are effective to close the channels 52 in the forward face of 15 plate 50 to define the completed guideways 11 above referred to for guidably receiving filler wires 13 of elongated cross-section and holding the same at a predetermined angle relative to the plane of the cloth into which these filler wires 20 are to be woven, to a lowered position wherein the teeth 55 are withdrawn from the cloth and the forward portions of channels 52 are opened to permit of the retraction of the comb assembly 25 backward to withdraw the channels from about 25 the filler strands 13 and to again elevate the comb teeth 55 to close the channels 52 preparatory to the subsequent injection of an additional filler strand therein.

The size and spacing of the slots 51 in back 30 plate 50 will of course be determined by the size of mesh of the material to be woven, the machine herein illustrated having been particularly constructed to fabricate cloth having a mesh of the order of insect screen, the spacing between slots 35 51 being about $\frac{1}{4}$ inch, and having a width of about $\frac{3}{2}$ inch.

As before stated the interlocking twists between the two warp wires 17 of each pair for locking the filler strands 13 in place are produced by two rows of quills referred to generally at 15 and 16. The backplate 50 is formed with enlarged vertically extending channels 57 (Fig. 12) converging with vertical slots 51 and serving to admit the forward noses of quills 15, 16, to a point 45 closely adjacent channels 52.

The quills are cylindrical in shape, being journaled adjacent their forward and rearward portions in bearing plates 58, 59 and geared together for synchronous rotation by circumferentially 50 formed gear teeth arranged in a particular manner to be described. Each quill is formed with a pair of diametrically disposed coaxial grooves or channels 60 (see Fig. 12) for guidably conveying its corresponding pair of warp wires from the rear end thereof to points of discharge on the forward nose of the quill. These channel guideways pass along the periphery of the quill through the troughs between substantially diametrically opposed pairs of teeth of the quill gear and are brought out in a slight curve 61 to the nose of the quill, the direction of curvature being generally clockwise on all of the quills. The purpose of this arrangement of guideways on the quills is to 55 discharge the respective warp wires of each quill at points lying on diameters of the quills, all of which diameters lie in parallel vertical planes at the time of discharge.

Each of the quills is further formed with a wedge-shaped forward nose 62 (see Fig. 12) to 70 facilitate its entry into channel 57 to a depth closely adjacent the filler strands 13 but spaced slightly out of contact with the channel wall with the long edges 63 of noses 62 all parallel and extending vertically. The guideways 60 discharge 75

the warp wires from the quills at the opposite ends of the edge 63 of the wedge-shaped nose 62, to a preceding interlocking twist 19 (Figs. 5, 6) thus defining a shed for the reception of a filler strand 13.

A special drive arrangement is provided for effecting the rotation of all the quills synchronously at successive intervals without releasing driving contact therewith. Referring particularly to Fig. 12, the upper row of quills 15 is provided with staggered but overlapping teeth 64 and 65 on alternate quills, while the lower row of quills 16 is provided with teeth 16a extending between bearing plates 58 and 59, the gear teeth of all of the quills being in driving contact. A rack 66 is positioned for engagement first with teeth 64 of the quills and is arranged to be driven to the right as indicated by arrow 61 a distance sufficient to rotate the quills 360° in a clockwise direction to produce the interlocking twist between the respective warp wires of each pair. Rack 66 is subsequently shifted backwards as indicated by arrow 68 in a direction parallel to the teeth thereon to a position in mesh with the teeth 65 of the rearwardly toothed quills and out of contact with teeth 64, preparatory to the subsequent movement of rack 66 to the left as indicated by arrow 69 to again effect the rotation of the forwardly geared quills 360° in a resumed clockwise direction to again produce a row of interlocking twists for tying in a previously injected filler strand 13. The rack is subsequently shifted to the front as indicated by arrow 70 to again bring the teeth thereof into engagement with the forward quill teeth 64 to thus complete a rectangular path preparatory to repeating the cycle.

In order to facilitate the shifting of rack 66 as indicated by arrows 68 and 70, and to make it possible for the rack teeth 66a on the rack 66 to engage the gear teeth of all of the upper quills 15 simultaneously, I have found it desirable to space the teeth 66a in an unorthodox manner. I have found that the unorthodox spacing of these teeth most conducive to satisfactory operation results when these teeth are spaced a distance equal to that exact divisor of the pitch diameter of the quills most nearly approximated by the product of the pitch diameter of the quill gear teeth and the factor 3.1416 divided by the number of gear teeth on the quill. It is to be noted that the orthodox spacing of these teeth would consist in spacing the same apart an amount equal to the product of the pitch diameter of the quills and 3.1416 divided by the number of gear teeth on the quill, which orthodox spacing would obviously make it impossible for the rack 66 to engage all of the quills 15 simultaneously for any orthodox spacing of these quills.

With my improved spacing of the teeth 66a, these teeth are always maintained in positive contact with the quill gear teeth so that there is never any lost motion, while at the same time the rack 66 is readily shifted from teeth 64 to teeth 65 without lifting the rack from contact with the quill gear teeth.

In the present machine employing a pitch diameter d of $\frac{1}{4}$ " and twelve teeth on the quill, the teeth 66a have their centers spaced apart a distance e of $\frac{1}{16}$ ". In other words, there are more teeth 66a on the portion f of the rack 66 than would be present on an orthodox rack, namely, 8 teeth where an orthodox rack would have 7.639+ teeth (Fig. 10).

The transition of the rack from teeth 64 to

teeth 65 and back again, is further facilitated by chamfering the ends of the rack teeth as well as the inner ends of teeth 64 and 65 in a well known manner.

Turning next to the power operating means 5 for moving the comb assembly 10 backward and forward relative to the quills 15 and 16 and for causing the comb 55 to be raised and lowered on the backplate 50 and also to the power means for effecting the movement of the rack 66 in the above 10 described rectangular path, there is provided a plurality of cams driven simultaneously from a common power shaft, these cams acting upon the necessary levers through rises and falls on the 15 cams for causing the requisite movements of the parts.

A cam 71 (Fig. 4) is effective to move the entire comb assembly 10 forward and backward about pivotal supporting shaft 72 by operating on roller 73 mounted on the end of link 74, adjustably connected to arm 75 projecting from the rear of backplate mounting member 76. Backplate mounting member 76 is connected to pivotal supporting shaft 72 through the medium of journal members 77 carried on the underside 25 thereof, supporting a transverse shaft 78 which in turn is connected by a plurality of supporting links 79 to transverse supporting shaft 72. This shaft in turn is journaled in comb assembly bearing brackets 80. These brackets are adjustable forwardly and backwardly on the base 81 in connection with the adjustment of the weaving head for tying in the flat filler strips at different angles to the plane of the cloth, which arrangement will later be described in detail. Once comb assembly bearing bracket 80 has been adjusted for a particular angle of cloth, the subsequent movement of the comb assembly forward and backward takes place about the shaft 72 as a pivot, shaft 78 being merely an adjusting pivot, 40 no relative movement about this shaft taking place during the normal operation of the machine.

A second cam 82 (Figs. 8 and 9) located adjacent cam 71 is effective to cause the vertical reciprocation of comb mounting plate 83 by driving roller 84 mounted on the end of link 85, adjustably connected to arm 86, pivoted intermediate its ends on pin 81, journaled in the above referred to arm 75 and this arm 86 acting through roller 88 on the forward end thereof to raise and lower the comb. Comb mounting plate 83 is slidably received on the forward face of backplate mounting member 76. Plate 83 supports comb 54 in the upper portion thereof. This comb is 55 made of a high grade of steel and the teeth 55 are machined therein to a very fine degree of accuracy.

Actuating cams 71 and 82 are mounted on the same shaft 89 driven from a common power shaft 90 (Fig. 1) through reduction gearing 25 by electric motor 24 positioned at the rear of the machine. I contemplate the use of two sets of cams each set being identical in form and located adjacent the respective ends of the shaft 65 89 for the purpose of effecting a better balance in the operation (see Fig. 1).

The rollers carried on the ends of links 74, 74', 85 and 85' are held in contact with the corresponding cam by suitable means such as adjustable tension springs 75a and 88a.

The means for effecting the shifting of the rack 66 from the forward quill gear teeth 64 to the rear quill gear teeth 65 and back again comprises a central cam 91 (Fig. 4) having an ap- 75

propriately formed groove 92 therein engaging roller 93 for oscillating forward and backward rack shifting lever 94 mounted on fixed pivot 95 and carrying roller 96 on the opposite end thereof in driving engagement with rack carrier 97. I contemplate the use of two of these cams 91 one adjacent each end of the supporting shaft 98 for the purpose of balancing the operation of the machine.

For effecting the movement of rack 66 to rotate the quill gears there is provided a second or intermediate cam 99 (Figs. 1, 2 and 7) having an appropriately formed cam groove 100 in the face thereof for driving cooperation with the roller 101 mounted in one end of a rack driving lever 102 pivoted intermediate its ends on pin 103 and engaging the rack carrier 97 through a roller 104 carried on the other end thereof for driving the rack back and forth to effect rotation of the quills. Cam 99 is also mounted on shaft 98, the latter being journaled in brackets 105 extending from face casting 106 and base casting 106a. Shaft 98 is likewise driven from power shaft 90 but is connected through a reduction gearing whereby cams 91 and 99 are driven at one-half the speed of cams 71 and 82. The reason for this, together with an understanding of the particular sequence of operation of the above described elements of my improved weaving machine will be clearly brought out in the description of operation.

It appears to be sufficient at this point to merely state generally that flat strips 13 are first inserted in the guides 11 of the comb assembly 10. The cams 71 next become effective to move the entire comb assembly slightly forward to give the noses 63 of the quill sufficient clearance in order that they may be rotated within grooves 57. This movement takes place entirely about pivots 72, the complete comb assembly being shifted forward in the present case a distance of the order of .030 inch relative to the axially stationary quills 15 and 16.

Cam 99 next becomes effective to drive the rack 66 for rotating the quills 360° to produce the integrating twists in the warp wires for locking the filler wire in place. Following this twisting operation, cam 71 again becomes effective to produce a further forward movement of the cam assembly for advancing the cloth a short distance in the present instance about .060 inch, while comb elevating and lowering cams 82 (Figs. 8 and 9) operate to lower comb teeth 55 from between the warp wires and to uncover the channels 52. Cams 71 next become effective to withdraw the entire comb assembly backward, thus removing the channels from about the filler wires 13 while cams 82 become effective to again raise the comb teeth 55 to a position between the warp wires where these teeth again cover the forward portion of channels 52 to define guideways 11 for the reception of additional filler wires.

Filler ribbon angle control

My machine is constructed in a special manner providing for the necessary adjustment in order to tie in the elongated filler ribbons or strips with their major surfaces disposed at any desired angle to the plane of the fabric. Where, for example, the screen produced by my machine is to be used as window screen for the purpose of controlling the entry of light rays, as well as keeping out insects, it is important that the flat or elongated filler wires 13 be woven into

the cloth at the particular angle found to give optimum conditions of light control for the particular exposure on which the screen is to be employed.

I have discovered certain fundamentals, the observance of which solves the otherwise difficult problem of perfecting a firm tie or twist between the warp wires 17 when weaving cloth having the flat filler strips 13 disposed at an angle to the cloth other than a right angle but not lying in the plane of the cloth.

The particular angle C at which the comb assembly back plate 50 (Figs. 4 and 5) must be inclined relative to the axis X of the quills in order to tie in the flat filler wire at a particular desired angle to the plane of the cloth, is determined by the structure of the cloth itself. I have discovered that the controlling factors are: (1) the desired angle of the flat filler wire to the plane of the cloth; (2) the position of the center of the twist relative to the flat filler wires; (3) and maintenance of the center of the twist and the bisector of the shed angle on the center line of the quill. The application of these factors involves simply laying out to scale a section of the desired cloth and employing the relationships indicated in adjusting the machine to the proper setting for weaving the particular cloth. This layout readily reveals the location of the bisector of the shed angle, as well as the proper inclination of the back plate 50 to the axis of the quills. These conclusions, of course, are capable of being readily checked by simple trigonometric calculations. It then becomes a mere matter of supporting the comb assembly in the indicated relationship.

Referring now to the particular construction of my weaving head, provisions for the necessary adjustment of the comb assembly 10 relative to the noses of the quills in order to satisfy the above stated fundamentals, will now be described. The relative position of the elements for weaving cloth having the elongated filler wires at a right angle to the plane thereof, is indicated in Figs. 3, 7 and 8, while the adjustment of these elements to a second position for weaving cloth, wherein the flat filler wire is tied in at 10 degrees off vertical or 80 degrees to the plane of the cloth, is indicated in Figs. 4 and 5.

For weaving right angle cloth, the back plate 50 is maintained exactly perpendicular to the axis of the quills with the back faces of guide channels 52 exactly parallel with the forward edge 63 of the quills. Supporting links 79 are positioned, as indicated in dotted lines in Fig. 4, and in solid lines in Figs. 3, 7 and 8. The base nuts 107 are tightened to hold the base 80 in place while the clamping nuts 77a and 79a are tightened to prevent relative movement about shaft 78. The machine is now in position for weaving right angle cloth, the forward movement of the comb assembly taking place about pivot 72, as before stated.

The adjustment of the machine for weaving the flat strips into the cloth at an angle less than 90 degrees to the plane of the cloth, will now be described. The adjusting nuts 74a and 85a are next given several turns preparatory to the forward tilting of the back plate 50 relative to the noses of the quills. The clamping nuts 77a or 79a are withdrawn sufficiently to permit of the adjusting of links 79 counterclockwise about the axis of shaft 78, and the shifting of the base 80 to its solid line position in Figs. 4 and 5, where it is fastened in place. The shaft 75

78 is next moved forward relative to the shaft 89 to a point where the back plate 50 on mounting plate 76 is rearwardly inclined at an angle C of three degrees to the vertical or with the back face of channels 52 located in the forward side of plate 50, inclined at an angle of three degrees to the forward noses 63 of the upper row of quills. The centers of edges 63 of the quill noses are spaced substantially the same distance from the back edge of slot 57 as in the case of right angle cloth which, in the present machine, is about 0.015 inch. In the arrangement disclosed in Fig. 5, the lower deck of quills is not in operation when weaving angle cloth, due to the fact that the lower row of quills are spaced too far away from the guide slot 11 as a result of the necessary tilting of the back plate. However, both rows of quills may be simultaneously employed in weaving angle cloth simply by replacing the lower row of quills 16 with quills having a slightly longer nose as indicated in dotted lines in Fig. 5. These replacement quills for the lower deck 16 must have the noses thereof in the same relation to the lower guide slots 11 as the noses of the upper quills 15 have to the guide 11 corresponding thereto.

The bolts are next tightened into place to prevent relative movement about shaft 78 and to fasten base 80 in its new position. Due to the fact that the forward tilting movement of the backplate 50 results in moving the axis of rollers 73 and 84 out of the same vertical plane with the axis of shaft 89, it is necessary to substitute new links 74' and 85' for links 74 and 85. With the above changes, the weaving head is set for producing cloth with the flat filler wires tied in at 80 degrees to the plane of the cloth or 10 degrees off of vertical. With the backplate 50 in the above described positions, namely, tilted back at 3 degrees, the cloth will come off of the machine at 7 degrees below the horizontal, or at an angle of 7 degrees with respect to the quills, the angle at which the flat filler wires are tied in to the cloth being 80 degrees relative to the plane of the cloth.

While the trigonometric calculations necessary in order to determine these particular settings are within the skill of the engineer, I have found it advisable to make the necessary gauges for repeating these settings once they have been determined. There is provided preferably one gauge for setting the radius between shaft 78 and shaft 89 for each angle of cloth, and corresponding gauges for the elevation of shaft 78 and the angle of backplate 50 relative to the forward noses of the quills. With these three gauges for each different angle of cloth to be woven, it becomes a very simple matter to quickly set up the machine for weaving the particular angle of cloth.

With the above stated fundamentals, together with the two examples of adjustment described, it is a relatively simple matter to determine the necessary adjustments to satisfy these conditions 65 in order to weave any desired angle of cloth.

By way of example, there is indicated in Fig. 5, a piece of 10 degree cloth, bringing out the above referred to controlling factors. The filler wire 13 is positioned with its major surfaces at 70 an angle C equal to 80 degrees to the plane of the cloth. The center of the interlocking twist is located slightly above a line erected perpendicular to the flat wire at its center. The bisector of the shed angle a , b , passes through the 75 center of the twist, and coincides with the axis

X of the quill, angle a being equal to angle b . It is found that with this disposition of parts, the flat filler wire is positioned at an angle c of approximately three degrees to the noses of the quills.

While I have disclosed for the purpose of illustration a specific form of comb structure and actuating means therefor, and also use this form in actual practice, I nevertheless contemplate other equivalent forms of comb mechanism, 10 capable of performing the same broad function as the present structure, as coming within the broad scope of my invention.

It is particularly pointed out that certain of the more specific features of the present comb 15 and comb actuating structure are not my invention, the same being covered by an application of one Heinze, Serial No. 239,257. These features include the specific arrangement of comb 55 being vertically slidable on the forward face 20 of backplate 50, in combination broadly with a row of quills operable in openings in the backplate 50 (Fig. 11). Also excluded as not constituting part of my invention is the further and more specific feature of forming the upper 25 portion of backplate 50 with a forwardly extending portion defining an inclined surface 50a co-operating with a complementary inclined surface 55a on the upper end of the comb teeth 55 for insuring the snug closure of the forward 30 side of channels 52 by the teeth 55 when the same are raised into position with inclined surface 55a in contact with inclined surface 50a. Still another structure that is not my invention, is the specific arrangement of cams 71 and 82 35 in combination with the specific arrangement of levers 75 and 86 for operating the comb assembly.

Warp wire supply assembly

Referring now in greater detail to the arrangement of means forming the warp wire supply 40 means B, geared tables 21 (Figs. 1, 3, and 18 to 20) are provided with forwardly extending brackets 125 each supporting a shaft 126 extending at right angles to the axis of a driving shaft 127 for the table. Mounted on shaft 126 45 are coaxial spools 22 and 23 above referred to, for supplying a pair of warp wires 17 to the corresponding quill. The warp wires 17 are brought out through openings in bracket 125, and lead into a pair of flexible conduits 128 communicating with the openings in the bracket 125. These flexible conduits 128, containing the warp wires 17, connect with anti-friction conduit bearing members 129 in centralizing panel 130. Shafts 127 extend through the back side of upright supporting panels 131 to gears 132, 133, 50 driven through chains 26, and 134 from reduction gearing 25 by motor 24 which also drives the weaving head operating cams. As before 55 stated, the spool tables 21 are rotated the same total number of rotations as made by the quills, for the purpose of preventing the twisting together of the pairs of warp wires behind the quills.

The warp wires 17 are preferably unwound from opposite sides of spools 22 and 23 to thus effect the rotation of these spools in the opposite direction. With the feed from the spools arranged in this way, the spools tend to effect a 70 braking action on each other. As an additional braking means for the spools, I may provide the brake indicated generally at 136 (Figs. 18 and 22). This brake for the respective spools preferably comprises a pin 137 mounted for recipro- 75

cation in a suitable opening formed in the bracket 125 having its outer end contacting the side wall of its associated spool for frictional engagement therewith. As a means for urging pin 137 into contact with the side wall of this spool with a predetermined pressure, I prefer to employ a spring 138, one end of which is attached to bracket 125 as by means of a screw 139, the other end of which is in contact with the outside end of pin 137 and is effective to urge the same into contact with its associated reel. Adjusting screw 140 is threadably mounted in the wall of spring 138 and adjustably contacts bracket 125 for determining the degree of pressure exerted by spring 138 upon pin 137.

A special arrangement for effecting the ready removal and replacement of spools 22 and 23 is provided comprising the forming of shaft 126 with an annular depression 141 (Fig. 21) adjacent the end thereof. Cooperating with annular depression 141 is a locking member referred to generally at 142 and comprising a body formed with a passage for receiving the end portion of shaft 126 and a chamber for receiving a plunger 143 urged into engagement with annular depression 141 by means of spring 144.

The number of panels and the number of tables 21 will be determined by the number of quills to be supplied, there being one table 21 for each quill. The machine disclosed herein is arranged to weave two pieces of cloth simultaneously of 48" width having four pairs of warp wires to the inch. This results in 386 tables 21 which are divided between three vertical panels 131. The flexible conduits 128 carrying warp wires 17 pass forward to bearings 129 in centralizing panel 130, as above pointed out. The conduits 128 leading from the rear ones of the panels 131 pass through suitable openings 145 (Fig. 20) in the forward panels, these openings being located in the open spaces between the turn tables 21.

A special arrangement of the rotatable tubular casings is provided for conducting the warp wires from the centralizing panel 130 to the rear of the quills 15 and 16 (Figs. 13 to 17). This arrangement is of particular importance in the present machine due to the small spacing between the elements resulting from the construction of the machine for weaving cloth of a fine mesh. This arrangement of rotating tubes comprises a first outside separating casing or tube 150, the rear end of which is flared at 151 to receive the forward ends of the flexible conduits 128 in the spaced relationship in which these conduits are mounted in bearings 129. A pair of separating casings 152 extend from within outer casing 150 at a point adjacent the ends of flexible conduits 128 to the forward end thereof located at 60 a point adjacent the rear end of the associated quill. The function of this pair of casings is to conduct the pair of warp wires therethrough and to maintain the same separated prior to their discharge from the casing to the rear end of their respective quills. The forward end of outside casing 150 is fastened to the rear end of its corresponding quill by a universal connection in the form of a pair of metal pins or steel wires 153 axially adjustable in the end of casing 150 by crimping the casing thereabout to define a slip joint. The result of this arrangement is to fasten the separating tubes 152 into the casing on a diameter lying substantially at right angles to the diameter on which the steel wires 153 are located. The forward ends of the steel wires

153 are fastened in suitable openings in the rear end of their corresponding quills on a diameter thereof. This arrangement gives a universal joint connection between the forward end of casings 150 and the respective ones of the quills 15 and 16.

As a means of further facilitating the control of the movement of the warp wires through the weaving head, there is provided a tensioning means on the rear end of each of the quills for applying a predetermined resistance to the passage of the warp wires along the guides in the quill, and the further provision of an arrangement for applying a take-off tension to the woven cloth. The tensioning means applied to the rear end of the quills is preferably in the form of a coiled spring 154 effective to contract and force the warp wires against their guideways 155 in the rear end portion of the quills 15 and 16. The arrangement for effecting a predetermined pull-away of the material from the weaving head is indicated as composed of an adjustable weight W (Fig. 5) applying a force to the take-off rolls 156. While the machine is new, I have found that a tension of one pound in each of the coil springs 154, and a constant pull-away force of 70 pound in the case of the instant machine, produces very satisfactory results. The pull-away force will, of course, be dependent upon the particular machine and will be varied to give optimum conditions of operation as the machine is broken in. The particular form and arrangement of the tensioning means on the rear end of the quill constitutes part of the present invention only broadly in the application thereof to the present machine, the specific modification shown being an invention of one Stanley Johnson and covered by application Serial No. 239,232 filed simultaneously herewith.

Filler ribbon supply assembly

40

Referring in greater detail to Figs. 23 through 27, the preferred forms of filler wire forming and injecting means comprises a pair of flattening and injecting rolls 28 and 29 which receive round wire from stationary spools 32 and 33, and roll the same to produce filler wires 13 of elongated cross-section and inject the same into the guideways formed in the comb assembly.

The spools of round wire remain stationary, the wire being drawn from the side of the spool over guides, indicated generally at 201, 202, thence to a guide 203 on the mill table 204, from which it is delivered to the flattening faces of rolls 28 and 29.

The spool assemblies 32 and 33 preferably comprise a cylinder 201a supported on a base 201b and provided at its open outer end with a bracket 202c supporting guide bar 202a. The guide assembly referred to generally at 202 is preferably composed of a bar 202a having a pair of radially extending pins 202b effective to confine the wire therebetween (Figs. 23 and 24).

The stationary supply spool arrangement for feeding the round wire to the flattening rolls is of particular advantage in the relation disclosed, since it renders unnecessary the usual arrangement of rotatable spool support and brake therefor, and otherwise simplifies this portion of the machine. The use of this stationary feed is made possible in the present combination by virtue of the fact that the round wire that is drawn off of the side of stationary spools 32 and 33, even though becoming twisted in being so drawn, the passage of this twisted wire through the

45

50

55

60

65

70

75

flattening rolls results in a wire of elongated cross-section that is completely acceptable for the present purpose.

While I have disclosed this specific arrangement of spools 32 and 33 for feeding round wire to the flattening rolls 28 and 29, and use the same in practice, I nevertheless contemplate other arrangements for feeding a round wire to the flattening rolls as coming within the broad scope of my invention. The specific arrangement of supply assemblies 32 and 33 providing for these rolls remaining stationary and the round wire being fed from the side thereof to the flattening rolls is not my invention but is covered in a co-pending application of one Stuerer, Serial No. 239,242.

Flattening roll 29 is mounted on shaft 205 supported in suitable journals on the mill frame indicated generally at 206 (Figs. 23 and 26). Tangential flattening roll 28 is journalled in a unitary yoke 207 (Figs. 23 and 25), and geared to tangential flattening roll 29 through gears 208 and 209. Yoke 207 is supported in guideway 207a for moving flattening roll 28 relative to flattening roll 29 in order to adjust the thickness of the elongated filler wire strips. The position of yoke 207 is controlled by adjusting screw 210 for varying the thickness of the flat filler wire produced thereby.

The flattening rolls are driven periodically in sequence with the operation of the comb and quill assembly through a ratchet and pawl clutch including a ratchet gear 211 (Fig. 25), and pawl 212, mounted on a plate 213 connected to a gear 214 driven by a rack 215, in turn motivated by a fluid motor indicated generally at 30.

The fluid motor 30 is of a well known type comprising a reciprocable piston connected by a piston rod 218 through the usual liquid seal (not shown) to the rear end of the rack 215 to which it is in turn fastened by any suitable means such as a threaded connection 219.

Fluid power for operating piston 217 is supplied by a pump 220 through a two-way valve 221 effective to control the supply of pressure to either side of the piston depending upon the position of the valve 221. This two-way valve is under the control of a cam 222 mounted on shaft 89 along with the comb assembly actuating cams 71 and 82. Cam 222 becomes effective by means of rise 222a at the beginning of the last 180 degrees of rotation of shaft 89 to depress link 223 which in turn operates bell crank 224 to shift valve 221 to the right, and thus cause the same to deliver fluid pressure from pump 220 to the rear side of piston 217. Bell crank 224 is further effective to move control rod 226 against the resistance of compression spring 229 (Fig. 25) to a point where collar 227 carried on the forward end of control rod 226 permits link 228, urged by spring 228a, to drop in front thereof to thus hold control valve 225 in the position to which it was moved. Piston 217 is now subjected to fluid pressure, and drives rack 215 to the left in Fig. 25 until cam 230 carried on the forward end of rack 215 contacts the upper end of link 228, thus lifting the same out of locking relationship with respect to collar 227 (see Fig. 26), and permitting spring 229 to shift plunger 225 of valve 221 to the left in Fig. 25, thus changing the delivery of fluid pressure to the opposite side of piston 217, and causing the return of the rack preparatory to again driving the rolls. The ratchet and pawl 211 and 212 operate to drive the rolls in one direction only, namely, in the

feeding direction and permit of the free return of the rack to its initial driving position. Provision for adjustment in the operation of locking lever 228 is made by hinging the two ends of the lever at 228b and clamping these two end portions together in their adjusted positions by clamping screw 228c.

While I have shown a ratchet and pawl one-way drive arrangement, it is quite apparent that other forms of one-way drive may be employed, such for example, as the well known free-wheeling clutch disclosed in the patent to Leschorn, No. 1,684,838.

Adjustment of the rolling mill assembly to provide for the proper registry to the discharge guide 231 and cut-off block 35 with the receiving guideways 11 of the comb assembly when the machine is adjusted for weaving fabric having the flat filler wires locked therein at different angles to the plane of the fabric, is provided by the special construction of the mounting for supporting the mill frame 206 from the weaving head main frame indicated generally at 233 (Figs. 2 and 26). This arrangement includes a first horizontal guideway defining member 234 provided with a pair of opposed horizontal tongues 235 and 236 adapted to guidably confine an intermediate adapter member 237. The adapter 237 is horizontally adjusted along guides 235, 236 by means of screw 238 under the control of handwheel 239 (Fig. 25). Adapter 237 is formed with vertically confining guide tongues 240 and 241 for receiving and confining an auxiliary adapter member 242 which is vertically adjustable along guides 240, 241 by means of adjusting screw 243. Auxiliary adapter 242 has shaft 244 journalled therein which in turn supports rolling mill frame 206. The rolling mill frame is made adjustable about shaft 244 and relative to auxiliary adapter member 242 by provision of arcuate slots 245 formed in mill frame member 206 for cooperation with clamping screws 246 passing through these slots and effective to clamp the frame member 206 to auxiliary adapter member 242.

It will thus be seen that the rolling mill frame 206 can be readily adjusted horizontally, vertically and pivotally to bring the delivery channel of the shearing block 35 into precise alignment with the receiving guide-way channels 11 of the comb assembly.

While I have disclosed an arrangement for fabricating the flat filler ribbons simultaneously with the operation of injecting the same into the shed, and employ this arrangement in practice because of its novel advantages, I, nevertheless, contemplate the use of machines wherein pre-formed filler wires are employed as coming within the broad scope of my invention. The simultaneous forming and injecting of flat filler wire as well as the control of the mill is not part of my invention, these features being covered in the co-pending applications of Heinze, Serial No. 239,257 and Berg, Serial No. 239,236.

Sequence of operation

Referring to Figs. 28a through 32f wherein I have indicated schematically the successive relative positions of the parts of the weaving head in weaving a piece of cloth, the solid lines in Figs. 28a-28g represent the position occupied by the parts just prior to the beginning of the interlocking twist operation. Comb teeth 55 are in raised position on backplate 50 of comb assem-

bly 10, thus closing guide channel 52 in back-plate 50 to define guide 11. A filler ribbon or wire 13 of elongated cross-section has previously been injected in position in the guide 11. The 5 wedge-shaped noses 62 of quills 15 are each positioned within the vertically aligned grooves 57 in the backplate 50, but out of contact therewith. The lower row of quills 16 are omitted from Figs. 28a to 32f for simplification. The warp wires 17 10 pass along the diametrically disposed guideways in each of the quills to the ends of the wedge-shaped nose 62 thereof, thence to the preceding twist 19 to define a plurality of sheds embracing the previously injected filler wire 13.

15 The disposition of parts indicated in solid lines in Figs. 28a-28g will be referred to as the zero or starting point for purposes of reference.

As already pointed out in the detailed description, there is provided four cams for effecting the 20 sequence of operation of the weaving head, namely, forward and rearward rack shifting cam 91; rack reciprocating quill rotating cam 99; forward and backward comb assembly shifting cam 71; and comb raising and lowering cam 82, the 25 latter two cams being rotated at twice the speed of the first two for reasons that will appear from the operation of the machine. These cams are driven simultaneously from power shaft 90 as already pointed out.

30 The first step in the operation of the weaving head from the zero position, is the forward shifting of the entire comb assembly 10 about its pivot 72 (see also Figs. 3 to 8) to move the grooves 57 away from the wedge-shaped noses 62 of the 35 quills in order that the quills may be rotated for effecting the integrating twists 19. This movement is caused by a rise 71a during the first ten degrees of rotation of forward and backward comb assembly shifting cam 71 in its movement 40 from the zero position. Roller 73 rides up upon rise 71a to actuate arm 15 connected to back-plate 50 to thus move the comb assembly about its pivot 72, while rise 82a on comb raising and lowering cam 82 acts on roller 84 to effect a synchronizing vertical movement of comb teeth 55. During this ten degree arcuate movement of 45 cams 71 and 82, and the corresponding five degree movement of cams 91 and 99, the rollers in contact with the latter cams are inactive, or, in 50 other words, pass along idle or dwell portions of their respective cams. The withdrawn or forward position of the channeled backplate 50 is indicated in dotted lines in Figs. 28a-28g, while the initial position at the zero or starting point 55 is indicated by solid lines in the same figure. This method of presenting the transition from one position of the parts to a succeeding position will be followed in the subsequent figures.

A second important step in the operation of my 60 weaving head that takes place during the first ten degrees of rotation of cam 71, is the cutting off of the filler strip 13 adjacent its point of entry in guide channel 11. This cutoff operation is effected by the forward movement of the comb 65 assembly relative to a stationary shearing head or block 35 mounted on the rolling mill when the comb assembly is moved forward by the operation of rise 71a on roller 73. To facilitate this shearing operation, the comb assembly 10 has 70 mounted thereon knife blade 34 for more effectively shearing the filler wire 13 as the comb assembly 10 is moved forward (see also Figs. 23, 26 and 27).

75 Turning now to Figs. 29a-29f, the next step of effecting the integrating twist is illustrated.

The position of the shed forming portions 11a of the warp wires 17 at the beginning of this twisting step is indicated in solid lines, while the position of these wires following the rotation of the quills to produce the twist 19 is shown in dotted 5 lines. The rotation of the quills to produce this twist 19 is caused by a rise 99a on cam 99 during the next fifty degrees of rotation of this cam. This rise 99a operates on roller 101 to turn lever 102 about its pivot 103 to cause a sufficient movement of the quill rack 66 crosswise of the fabric to rotate the quills 360°. The rollers on the remaining cams ride on idle or dwell portions thereof during this quill rotation. The filler wire is now locked in place by the integrating twist 19 15 preparatory to the withdrawal of the comb teeth 55 and the repositioning thereof behind this filler wire, and the injection of a subsequent filler wire.

Progressing to Figs. 30a-30f, the third step in 20 the operation of the weaving head comprises a secondary forward shift of the comb assembly and the withdrawal of the comb teeth 55 from between the pairs of warp wires and from in front of guide channel 52 for the purpose of advancing and releasing the cloth. The position occupied by the parts of the comb and quills at the beginning of this step is indicated in solid lines, while the position occupied by the parts at the end of this step in the operation is indicated 30 in dotted lines. The secondary forward shift of the comb assembly is for the purpose of advancing the filler wire 13 and the cloth to a position slightly beyond that occupied at the beginning 35 of the operation taking place in Figs. 29a-29c and 29f, and is effected by a rise 71b on cam 71 during the next 30 degrees of its rotation.

The dropping of the comb teeth 55 to clear the cloth and the guide channel 52 is begun simultaneously with the above referred to secondary forward movement of the comb assembly and is caused by a rise 82b during the above referred to thirty degrees of arcuate movement of cam 82. Rise 82b acts on roller 84 mounted on the outer end of lever 85 (see also Fig. 8), the forward end 45 of which carries a second roller 88, causing the same to lower comb teeth 55 on backplate 50. The parts are now in the position indicated by dotted lines in Figs. 30a-30f with the comb teeth 55 in the wide open position, and the comb assembly 10 advanced to its forward-most position relative to the noses of the quills, preparatory to the rearward movement of the comb assembly and the lifting of the comb teeth 55 behind the 50 filler wire 13 to again close the channel guide 52 55 preparatory to the reception of a subsequent filler wire 13, as will now be described in connection with Figs. 31a-31f.

Proceeding now to Figs. 31a-31f, the next step in the operation comprises the rearward movement of the comb assembly, withdrawing rearwardly guide channels 52 from about filler wire 13 and the raising of the comb teeth 55 behind filler wire 13 into their original elevated position to again close channel 52 to define guide 60 and holding means 11 for the reception of a subsequently injected additional filler wire 13. This movement is caused by falls on cams 71 and 82 respectively. Again the initial position of the parts at the beginning of the operation illustrated in Fig. 31 is shown by solid lines while the final position of these parts is indicated in dotted lines. Fall 71c on cam 71 during the first ten degrees of the operation illustrated in Figs. 31a-31f, allows the roller 73 to be lowered to its 65 70 75

normal dwell or idling level to thus retract the comb assembly to its rearmost position with the quill noses 62 in their deepest position within the grooves 57 in backplate 50. Fall 82c on comb actuating cam 82 becomes effective simultaneously with fall 71c to cause the raising of comb teeth 55. The operation of fall 82c overlaps that of fall 71c extending over an arc of forty degrees. The parts are now in the relative position indicated by dotted lines in Fig. 31 and prepared for the reception of a laterally injected filler wire 13 into the guide 11 defined by channel 52 and comb teeth 55.

Passing now to Figs. 32a-32f, the last step in the operation of my machine through a complete cycle comprises the injection of a filler wire 13 into the guide 11 and the shift of rack 66 from engagement with the forward quill gear teeth 64 to engagement with the rear quill gear teeth 65 (see also Fig. 12).

Hydraulic motor control cam 222 (see also Fig. 25) becomes effective through rise 222a to force roller 223a downwardly to thus initiate the operation of piston 217 to drive rack 215 to the left in Fig. 25 and thus cause flattening rolls 28 and 29 to form and feed a flat filler ribbon into guide 11. Control bar 226 upon being moved to the left in Fig. 25, is locked in this position by latch 228 cooperating with collar 227 and remains so locked until cam 230 carried on the end of rack 215, engages the roller on the outer end of latch 228 to release the same from engagement with the collar. Upon the control bar 226 being thus released, spring 229 becomes effective to shift piston 225 of reversing valve 221 to the right in Fig. 25, to thus cause a reversal of flow to the forward side of piston 217 of motor 30 and thus in turn cause the rack 215 to be driven to the right in Fig. 25 preparatory to again driving the feeding rolls 28 and 29. The forming rolls 28 and 29 are not driven during this return stroke of rack 215, but are allowed to remain stationary due to the operation of ratchet and pawl mechanism 211, 212 and 213.

A second operation that takes place simultaneously with the forming and feeding of a flat filler ribbon is the shifting of rack 66 from engagement with the forward teeth 64 to engagement with the staggered rear teeth 65 as indicated by arrow 68 (Fig. 12). This shift is effected by a cam groove 91 on each of the two rack shifting cams 91 acting on roller 93 to turn lever 94 about its pivot 95 to shift rollers 96 on the other end thereof from its solid to its dotted line position. (See also Fig. 4.) Roller 96 operates to shift rack carrier 97 rearwardly as indicated by arrow 68 in Fig. 12. The return shift indicated by arrow 70 is effected at a subsequent time by corresponding cams 91b formed on cam 91 and likewise cooperating with roller 93 on lever 94.

During the above operation of forming and feeding a filler ribbon 13 and effecting a shift of the rack 66, the remaining cams 71, 82 and 99 present idle or dwell portions of their surfaces in contact with their respective rollers.

When cams 71, 82 and 222 have passed through the 180° devoted to these last two operations comprising the last step, the apparatus is again at the zero or starting point preparatory to repeating the above described cycle of operations. It will be noted that the subsequent tying step will be effected by the rack 66, which is now in engagement with the teeth 65 of the rearwardly geared quills 15, being shifted in the direction in-

dicated by the arrow 69 which is opposite to the above described shift indicated by arrow 67. However, since the teeth 64 and 65 overlap the respective quills will be driven in the same direction as that in which they were driven for effecting the above described locking twist, namely, quills 64 will be rotated clockwise and quills 65 will be rotated counterclockwise.

No attempt is made in Figs. 28a to 32f to bring out the complete detailed construction of each of the cams, since to do so would unduly confuse the reader in attempting to understand the fundamental movements involved. The further details as to the formation of these cams is brought out in the master timing chart shown in Figs. 33a and 33b wherein the rises, dwells and falls on each cam are indicated in their arcuate relationship in a composite manner.

Referring to Figs. 33a and 33b it will be seen that in the actual embodiment of the machine, section 71b of comb assembly forward and rearward shifting cam 71 is composed of a first 10° rise indicated at N followed by a 20° pause or dwell portion indicated at O, the function of the former being to effect the secondary forward movement of the comb assembly, while the function of the latter is to maintain this forward position of the comb assembly while the comb teeth are being lowered to their lowermost position.

Section 71c is composed first of a 5° dwell or adjustment arc P followed by a 10° fall Q which is effective to bring the comb assembly back to its rearmost position. The adjustment arc P is introduced for mechanical reasons to give a brief time for adjustment of the parts before making the subsequent transition.

Section 82c of comb raising and lowering cam 82 is composed of first a 5° dwell arc R corresponding to dwell P of section 66c, and having the same function of providing for adjustment time; followed by a 10° synchronizing fall arc S, the function of which is to synchronize the movements of the comb assembly 10 including the movement of the comb 54; followed by another 5° pause arc T having the function of providing adjusting time before the next transition; and finally a 20° fall U to normal elevation effective to cause the lifting of the comb 54 back to its highest position on the backplate 50.

While I have indicated certain specific allotments of arcs on the cams for effecting the respective movements, it is quite apparent that this may be varied within a desired range to suit particular operating conditions.

It is to be understood that while I have described my invention in connection with a specific embodiment particularly constructed for fabricating wire cloth having a mesh of the order of insect screen, it is to be understood that this is by way of illustration and not by way of limitation. The same principles are subject to incorporation in a machine for weaving cloth having any desired size of mesh and the scope of my invention is defined solely by the appended claims which should be construed as broadly as the prior art will permit.

I claim:

1. The method of weaving a metal fabric which includes providing a plurality of pairs of warp wire strands, twisting the two strands of each of said pairs of strands together, feeding a filler wire of elongated cross section transversely to and between the respective strands of said pairs of warp strands, the long sides of said filler wire

being positioned at an angle to the plane of the fabric and then locked into said fabric by again twisting together the two strands of each of said pairs of warp strands on the opposite side of said filler strand and repeating the above to produce a strip of fabric.

2. The method of weaving a wire screen which comprises feeding a plurality of pairs of warp wires longitudinally of the fabric, twisting two wires of each of said pairs of warp wires together, injecting a filler wire of elongated cross section crosswise of the fabric and between the respective wires of said pairs of warp wire with the long sides of said filler wires inclined at an angle to the plane of the fabric, locking said filler wire in position by again twisting the two wires of each of said pairs of warp wires together on the opposite side of said filler wire, and repeating the above to produce a strip of fabric.

20 3. The method as defined in claim 2 wherein the adjacent pairs of warp wires are twisted in the opposite direction whereby to uniformly distribute the stresses throughout the fabric.

4. A weaving machine for weaving wire fabric composed of a plurality of definitely spaced warp wires extending lengthwise of the cloth and a plurality of definitely spaced filler wires extending transversely across the cloth, said machine including a weaving head, warp wire supply means, filler wire supply means and power means for driving said first named means, said weaving head comprising means for feeding said warp wires from said warp wire supply means and moving adjacent warp wires in opposite directions away from the median plane of the cloth to define a shed and guide means effective to guide a laterally injected filler wire into place within said shed and to hold the same in a predetermined spaced relationship to a preceding filler wire, said filler wire supply means comprising a supply spool of filler wire, a pair of injection rolls positioned adjacent the end of said guide means receiving wire from said spool and arranged to inject the same within said guide means and means for cutting said filler wire subsequent to injection, said warp wire moving means being again effective subsequent to the injection of a filler wire into said guide to move said respective adjacent warp wires in the opposite direction relative to the median plane of said cloth to thus lock said filler wire into said cloth, said guide means and spacing means comprising closure means subsequently operable to release said filler wire and further operable to reclose behind said filler wire preparatory to the injection of an additional filler wire, said power means being effective to operate said shed forming means, said guide means and said filler wire injecting means in sequence.

60 5. A weaving machine for weaving wire fabric composed of a plurality of definitely spaced warp wires extending lengthwise of the cloth and a plurality of definitely spaced filler wires of elongated cross section extending transversely of the cloth and positioned with their long sides at a predetermined angle to the plane of the cloth, said machine including a weaving head, warp wire supply means, filler wire supply means and power means for driving said first named means, said weaving head comprising means for feeding said warp wires from said warp wire supply means and moving adjacent warp wires in opposite directions away from the median plane of the cloth to define a shed and guide means for the reception of said filler strips injected later-

ally from the side of the cloth, said guide means being effective to position said filler wire a predetermined spaced distance from the preceding filler wire and with its long sides at said predetermined angle to the plane of the fabric, said 5 filler wire supply means comprising a spool of said filler wire, a pair of injection rolls positioned adjacent the ends of said guide means for injecting a filler wire therein, and means for cutting said filler subsequent to its injection, said 10 warp wire moving means being again effective subsequent to the injection of a filler wire to move said respective adjacent warp wires in the opposite direction relative to the median plane of said cloth to thus lock said filler wire into 15 said cloth, said guide and spacing means comprising closure means operable to release said filler wire and further operable to reclose behind said filler wire preparatory to the injection of an additional filler wire, said power means being 20 effective to operate said shed forming means, said guide means and said filler wire injecting means in sequence.

6. A weaving machine for weaving wire cloth composed of a plurality of definitely spaced pairs 25 of warp wires extending lengthwise of the cloth and a plurality of definitely spaced filler wires of elongated cross section extending transversely across the cloth with their longer sides disposed at an angle to the plane of the cloth, said machine including a weaving head, warp wire supply means, filler wire supply means and power means for driving said first named means, said weaving head comprising a row of rotatable quills 30 geared together and formed with longitudinal 35 diametrically spaced passages for feeding said pairs of warp wires from said warp wire supply means and for moving the respective warp wires of each pair in opposite directions away from the median plane of the cloth by arcuate movement 40 of said quills to define a shed, and guide means effective to guide laterally injected filler wires of elongated cross section into place within said shed and to hold the same in a predetermined 45 spaced relationship to a preceding filler wire, said filler wire supply means comprising a spool of filler wire, a pair of injection rolls positioned adjacent the ends of said guide means for injecting a filler wire therein and means for cutting said 50 filler wire subsequent to its injection, said quills being again effective subsequent to the injection of said filler wire to move the warp wires of each pair in the opposite direction relative to the median plane of said cloth to thus lock said filler 55 wire into said cloth, said guide and spacing means further comprising closure means operable to release said filler wire and operable to reclose behind said filler wire preparatory to the injection of an additional filler wire, said power means 60 being effective to operate said shed-forming means, said guide means and said filler wire injecting means in sequence.

7. In a wire fabric weaving machine, means for simultaneously feeding a plurality of pairs of 65 warp wires in a definite spaced relationship, means for feeding filler wires of elongated cross section transversely to and between the respective individual strands of each pair of warp strands, said means comprising guide means for 70 maintaining said filler strands at a predetermined angle relative to the plane of the fabric, means for twisting together the respective strands of each pair of warp strands between successive filler strands, whereby to produce a 75

firm fabric having uniformly distributed interstices therein.

8. A weaving machine for weaving wire fabric composed of a plurality of pairs of definitely spaced warp wires extending lengthwise of the cloth and a plurality of definitely spaced filler wires of elongated cross section extending transversely across the cloth with their major surfaces disposed at an angle to the plane of the cloth, said strips being locked in place within the cloth by integrating twists of said warp wires of each pair between successive filler wires, said machine including a weaving head, warp wire supply means, filler wire supply means and power means for driving said first named means, said weaving head comprising a row of rotatable quills geared together for simultaneous rotation and formed with substantially diametrically disposed coaxial guideways for feeding pairs of warp wires from said warp wire supply means and for twisting the two wires of each pair together to lock said filler wire in place in the cloth and define a shed for the subsequent introduction of an additional filler wire, guide means effective to guide a laterally injected filler wire into place within said shed and to hold the same in a predetermined spaced relationship to a preceding filler wire with its major surfaces at a predetermined angle relative to the plane of the cloth, said filler wire supply means comprising a spool of filler wire, a pair of injection rolls positioned adjacent the end of said guide means for injecting a filler wire therein and means for cutting said filler wire subsequent to its injection into said guide, said quills being rotatable subsequent to said injection of a filler wire to again twist the wires of each of said pairs together to thus lock said injected filler wire in said cloth, said guide and spacing means further comprising closure means operable to release said filler wire and further operable to reclose behind said filler wire preparatory to the injection of an additional filler wire, said power means being effective to operate said shed forming means, said guide means and said filler wire injecting means in sequence.
9. A weaving machine for weaving wire cloth composed of a plurality of definitely spaced pairs of warp wires extending lengthwise of the cloth and a plurality of definitely spaced filler wires of elongated cross section extending transversely across the cloth with their long sides disposed at a predetermined angle to the plane of the cloth and locked in position by integrating twists between the two wires of each of said pairs of warp wires, said machine including a weaving head, warp wire supply means, filler wire supply means and power means for driving said first named means, said weaving head comprising means for feeding said warp wires from said warp wire supply means and moving adjacent warp wires in opposite directions away from the median plane of the cloth to define a shed and guide means effective to guide a laterally injected filler wire into place within said shed and to hold the same in a predetermined spaced relationship to a preceding filler wire, said filler wire supply means comprising a pair of injection rolls positioned adjacent the end of said guide means for injecting the filler wire into said guide means, and means for cutting said filler wire subsequent to its injection, said warp wire moving means being again effective subsequent to the injection of a filler wire to move said respective adjacent warp wires in the opposite direction relative to the median plane of said cloth to thus lock said

filler wire into said cloth, said guide and spacing means further comprising closure means operable to release said filler wire and operable to reclose behind said filler wire preparatory to the formation and injection of an additional filler wire, said power means being effective to operate said shed forming means, said guide means and said filler wire forming and injecting means in sequence.

10. A weaving machine for weaving wire cloth composed of a plurality of definitely spaced pairs of warp wires extending lengthwise of the cloth and a plurality of definitely spaced filler wires of elongated cross-section extending transversely across the cloth with their long sides positioned at a predetermined angle to the plane thereof and locked in place by integrating twists between the wires of each of said pairs of warp wires between said filler wires, said machine including a weaving head, warp wire supply means, filler wire supply means and power means for driving said first named means, said weaving head comprising a roll of rotatable quills geared together for simultaneous rotation and each formed with diametrically disposed coaxial guides for feeding a pair of said warp wires from said warp wire supply means and effective upon rotation to twist the wires of each of said pairs together to lock a filler strip in position within said cloth and to form a shed for the reception of an additional filler strip, guide means effective to guide a laterally injected filler strip into place in said shed and to hold the same in a predetermined spaced relationship to a preceding filler wire and with its long sides at a predetermined angle to the plane of the cloth, said filler wire supply means comprising a pair of injecting rolls positioned adjacent the end of said guide means for injecting said filler wire into said guide means, and means for cutting said filler wire subsequent to its injection into said guide, said quills being rotatable subsequent to the injection of said filler wire to again twist each of the wires of said pairs of warp wires together to thus lock said filler wires into said cloth and to form a shed for the subsequent reception of an additional filler wire, said guide and spacing means further comprising closure means operable to release said filler wire incident to the advancement of the cloth and operable to reclose behind said filler wire preparatory to the injection of an additional filler wire, said power means being effective to operate said shed forming means, said guide means and said filler wire injecting means in sequence.
11. A weaving machine for weaving wire fabric composed of a plurality of pairs of definitely spaced warp wires extending lengthwise of the cloth and a plurality of definitely spaced filler wires of elongated cross-section extending transversely across the cloth with their major surfaces disposed at an angle to the plane of the cloth, said strips being locked in place within the cloth by integrating twists of said warp wires of each pair between successive filler wires, said machine including a weaving head, warp wire supply means, filler wire supply means and power means for driving said first named means, said weaving head comprising a row of rotatable quills geared together for simultaneous rotation and formed with substantially diametrically disposed coaxial guideways for feeding pairs of warp wires from said warp wire supply means and for twisting the two wires of each pair together to lock said filler wire in place in the cloth and define a shed for the subsequent in-

introduction of an additional filler wire, guide means effective to guide a laterally injected filler wire into place within said shed and to hold the same in a predetermined spaced relationship to a preceding filler wire with its major surfaces at a predetermined angle relative to the plane of the cloth, said filler wire supply means comprising a spool of filler wire, a pair of injection rolls positioned adjacent the end of said guide means for injecting a filler wire therein and means for cutting said filler wire subsequent to its injection into said guide, said quills being rotatable subsequent to said injection of a filler wire to again twist the wires of each of said pairs together to thus lock said injected filler wire into said cloth, said guide and spacing means further comprising closure means operable to release said filler wire and further operable to reclose behind said filler wire preparatory to the injection of an additional filler wire, said power means being effective to operate said shed forming means, said guide means and said filler wire injecting means in sequence, said warp wire feeding means comprising means for applying a predetermined resistance to the feeding of said warp wires and means for applying a predetermined pull to the finished fabric as it is being discharged from said weaving machine.

12. In a weaving head for weaving wire cloth, means for feeding a plurality of warp wires simultaneously in a substantially common plane and for moving warp wires in opposite directions relative to the median plane of the cloth for defining a shed, means cooperating with said feeding and moving means adapted to guidably receive a laterally injected filler wire within said shed and to space the same a predetermined distance from a preceding filler wire, said warp wire feeding and moving means being subsequently effective to move the respective ones of said warp wires in the opposite direction relative to the median plane of the cloth to thus lock said filler strip in said cloth.

13. In a weaving head for weaving wire cloth the combination of holding and spacing means adapted to guidably receive a filler strip of elongated cross-section and hold the same with its long sides positioned at an angle to the plane of the cloth and a quill assembly, each of said quills adapted to feed and twist together a pair of warp wires to define a shed for the introduction of said filler strip, said quills each adapted to again feed and twist together said pairs of warp wires subsequent to the introduction of said filler strip to lock the same in place in the cloth, said holding and spacing means comprising a closure capable of being opened to release said filler strip after it has been tied into the cloth by said twisting operation, and power drive means for controlling the sequence of operation of said closure and said quill assembly, said holding and spacing means comprising a comb element having teeth arranged to be introduced between the pairs of warp wires and filler strips for effecting the requisite holding and spacing thereof.

14. In a weaving head for weaving wire cloth, means for feeding a plurality of warp wires simultaneously in a substantially common plane and for moving different adjacent warp wires in opposite directions out of the common median plane of the fabric for defining a transverse shed, means adapted to receive and guide a laterally injected filler wire into said shed and to space the same a predetermined distance from a preceding filler wire, said warp wire feeding and

moving means being subsequently operable to move the respective warp wires in the opposite direction relative to the median plane of the fabric to define a second shed on the opposite side of said filler wire and thus lock the same into the fabric, said guiding and spacing means comprising a comb having teeth introducible between said warp wires and said filler wires for the purpose of determining the size of the interstices to be woven into the fabric and arranged to be withdrawn for the advancement of the fabric preparatory to the introduction of a subsequent filler wire and power means effective to produce the sequence of operation of said means.

15. In a weaving head for weaving wire cloth, the combination of holding and spacing means adapted to guidably receive a filler strip of elongated cross-section with its long sides positioned at an angle to the plane of the cloth and a quill assembly, each of said quills adapted to feed a pair of warp wires and move the same in opposite directions relative to the median plane of the cloth to define a shed for the introduction of said filler strip, said quills each adapted to again feed and move said pairs of warp wires in the opposite direction subsequent to the introduction of said filler strip to lock the same in place in the cloth, said holding and spacing means comprising a closure capable of being opened to release said filler strip after it has been locked into the cloth, and power driven means for controlling the sequence of operation of said closure and said quill assembly.

16. In a weaving head for weaving wire cloth, the combination of a row of rotatable quills adapted to feed pairs of warp wires and to twist the same together to form a plurality of sheds, means for guiding a filler strip of elongated cross-section into said sheds and holding the same in a predetermined spaced relationship to the preceding strip and with its long sides at a predetermined angle to the plane of the cloth, said quills being rotatable subsequent to the positioning of a filler strip to again twist said warp wires together to lock said strip in position in the cloth, said first named means comprising means movable from a position in advance of said strip to a position behind said strip subsequent to said twisting operation whereby to prepare for the introduction of a second strip therein and means for effecting said movement in timed relation to the twisting operation of said shed-forming quills.

17. In a weaving head for weaving wire cloth, the combination of a row of rotatable quills adapted to feed pairs of warp wires through diametrically spaced coaxial guides formed therein and to be simultaneously rotated to twist said warp wires of each pair together to form a plurality of sheds, means for guiding a filler wire of elongated cross-section into said shed and holding the same in a predetermined relationship to the preceding strip with its long sides at a predetermined angle to the plane of the cloth, said quills being rotatable subsequent to the positioning of a filler strip to again twist said warp wires together to lock said strip in position in the cloth, adjacent quills being geared together for rotation in the opposite direction, said first named means comprising means moved from a position in advance of said filler wire to a position behind the same subsequent to said twisting operation whereby to prepare for the introduction of a second filler wire therein, said opposite directions of twist being effective to balance the

stress instant to the twisting operation, and means for effecting the movement of said first named means in timed relation to the twisting operation of said shed-forming quills.

- 5 18. In a weaving head for weaving wire fabric, the combination of a row of rotatable quills adapted to feed a plurality of pairs of warp wires and to twist the same together to form a plurality of sheds, means for guiding a filler 10 strip of elongated cross-section into said sheds and holding the same in a predetermined spaced relationship to a preceding strip and with its long sides at a predetermined angle to the plane of the cloth, said quills being rotatable subsequent 15 to the positioning of said filler strip to again twist said warp wires together to lock said strip in position in the cloth, said first named means including a comb having teeth comprising at least part of said spacing and holding means for said 20 filler strips, and power operated means effective to withdraw said comb teeth from a position in front of a last introduced filler strip and reposition the same behind said last introduced filler strip preparatory to the introduction of an additional filler strip.
19. In a weaving head for weaving wire cloth, the combination of a row of rotatable quills having wedge-shaped noses adapted to feed a plurality of pairs of warp wires and to twist the 25 same together to form a plurality of sheds, means for guiding a filler strip of elongated cross-section into said shed and holding the same in a predetermined spaced relationship to a preceding strip and with its long sides at a predetermined 30 angle to the plane of the cloth, said quills being rotatable subsequent to the positioning of said filler strip to again twist said warp wires together to lock said strip in position in the cloth, said first named means comprising a backplate 35 having a transverse channel extending across the forward face thereof, a comb having teeth comprising at least part of said spacing and holding means for said filler strips and operating on the forward face of said back plate from 40 a position wherein the teeth of said comb extend between adjacent pairs of said warp wires and close said guide channel to a position wherein said teeth are lowered from between said adjacent pairs of warp wires and said channel is 45 opened, said backplate being further characterized by the provision of a plurality of parallel vertical channels intersecting said guide channel and diverging rearwardly for the purpose of facilitating the entry of the wedge-shaped noses 50 of said quills to a point closely adjacent said guide channel, whereby to facilitate the cooperation between said shed-forming quills and said guide channel, to present the maximum size of 55 shed for the introduction of said flat strip therein.
- 60 20. In a weaving head for weaving wire fabric, means for feeding a plurality of warp wires simultaneously in a substantially common plane and for moving adjacent warp wires in opposite directions relative to the median plane of the cloth 65 for defining a plurality of sheds, means cooperating with said feeding and moving means adapted to guidably receive a laterally injected filler wire within said sheds and to space the same a predetermined distance from a preceding filler wire, 70 said warp wire feeding and moving means being subsequently effective to move the respective ones of said warp wires in the opposite direction relative to the median plane of the cloth to thus lock said filler wire in said cloth, said arrangement 75 being further particularly characterized by the

provision of a plurality of said means, one above the other, whereby to form a plurality of fabrics simultaneously.

21. In a weaving head for simultaneously weaving a plurality of wire fabrics, means for feeding a plurality of warp wires simultaneously in a plurality of planes, one above the other, and for moving warp wires in opposite directions relative to the median planes of their respective fabrics for defining a plurality of sheds, means cooperating with said feeding and moving means adapted to guidably receive a laterally injected filler wire within the respective sheds of each fabric and to space the same a predetermined distance from a preceding filler wire, said warp 15 wire feeding and moving means being subsequently effective to move the respective ones of said warp wires in the opposite direction relative to the median plane of the respective fabrics to thus lock said filler strips to said fabric. 20

22. In a weaving head for weaving wire fabric, the combination of a plurality of superimposed rows of rotatable quills geared together and adapted to feed pairs of warp wires and twist the same together to form a plurality of sheds, means 25 for guiding a filler strip of elongated cross-section into each of the sheds formed by each row of said quills and for holding said filler strips in a predetermined spaced relationship to a preceding filler strip with major surfaces thereof at a pre- 30 determined angle to the plane of the respective fabrics, said quills being rotatable subsequent to the positioning of said filler strips to again twist said warp wires together to lock said strips in position in their respective fabrics, said first 35 named means comprising means movable from a position in advance of said strip to a position behind said strip subject to said twisting operation whereby to prepare for the introduction of subsequent strips therein and means for effecting said movement in timed relation to the twisting operation of said shed-forming quills.

23. In a weaving head for weaving wire fabric, a backplate formed with a plurality of openings therethrough for the passage of warp wires, a plurality of transverse channels on the forward face of said backplate intersecting said openings, a comb having teeth reciprocable on the forward face of said backplate from a position wherein said teeth pass between adjacent warp wires and close said channel to a position wherein said teeth are withdrawn and said channel is opened, feeding means adapted to feed said warp wires and remove adjacent warp wires in opposite directions away from the median plane of the fabric to define a plurality of sheds, said transverse channels being positioned within said sheds to guidably receive filler wires adapted to be injected from the sides of the fabric, said comb and channels being effective to hold said filler wires in spaced 60 relationship with respect to preceding filler wires, said warp wire feeding and moving means being operable subsequent to the introduction of said filler wires to move said respective warp wires in the opposite direction away from the median 65 plane of the fabric to thereby lock said filler wires into said cloth preparatory to the introduction of subsequent filler wires.

24. In a comb assembly for the weaving head of a wire fabric weaving machine capable of 70 weaving a plurality of pieces of fabric simultaneously, a backplate, a comb, a row of rotatable quills, said backplate being formed with a plurality of openings therethrough for the passage of a plurality of pairs of warp wires, said quills be-

ing positioned for feeding said warp wires therethrough and twisting the same together, said backplate being further characterized by the provision of a plurality of transverse channels on the 5 forward face thereof intersecting said first named openings, said comb comprising a plurality of teeth receivable between the pairs of warp wires and operable on the forward face of said plate to effect the opening and closing of said channels, 10 said comb and channels defining holding and spacing means for filler wires of elongated cross-sections adapted to be introduced therein with their major surfaces at an angle to the plane of their respective fabrics and positioned between 15 the wires of each of said pairs of warp wires whereby the twisting of said warp wires together by the rotation of said quills is effective to lock 20 said filler wires into said cloth, the subsequent opening of said guides by the movement of said comb being effective to release said filler wires therefrom, and power driven means for controlling the operation of said comb assembly and said quills in sequence.

25. In a weaving head for weaving wire fabric, the combination of a row of rotatable quills adapted to feed pairs of warp wires and to twist the same together to form a plurality of sheds, means for guiding a filler strip of elongated cross-section into said shed and holding the same 30 with its major surfaces at a predetermined angle to the plane of the fabric, said quills being rotatable subsequent to the positioning of said filler strips to again twist said warp wires together to lock said strips in position in said cloth, said guiding and holding means being effective to maintain the center of each of said twists on the center line of its respective quill and further effective to maintain the bisector of the angle defined by the shed wires converging in said twists 40 in such a position that the same coincide with the center line of their respective quill, whereby to effect a firm tie.

26. In a weaving head for weaving wire fabric, the combination of a row of rotatable quills adapted to feed a plurality of pairs of warp wires and to twist the same together to form a plurality of ties between the shed-defining wires, means for guiding a filler wire of elongated cross-section into said sheds and holding the same in a predetermined spaced relationship to a preceding strip and with its major surfaces disposed at a predetermined angle to the plane of the fabric, said quills being rotatable subsequent to the positioning of said filler wire to again twist said warp wires together to lock said filler wire in position in the cloth, said first named means including a comb having teeth forming part of said guide and holding means for said filler wires, and operable from a position wherein said teeth extend between said warp wires and close the forward portion of said guiding and holding means, to a position wherein said teeth are removed from between said warp wires for moving the fabric forward and releasing the same, said guiding and holding means being further particularly characterized by the fact that said elongated filler wire is positioned relative to the forward noses of said quills to maintain the center of the twist on the center line of the respective quills and to maintain the bisector of the angle defined by the shed wires passing back from said twist also on the center line of the respective quills.

27. In a weaving machine provided with means for guidably receiving and holding filler wires of 75 elongated cross-section with their major surfaces

disposed at a predetermined angle to the plane of the cloth and a row of rotatable quills for feeding a plurality of pairs of warp wires longitudinally of the fabric and effecting integrating twists of said warp wires between each of said filler wires, 5 the combination therewith of a supporting means for said guiding and holding means to facilitate the adjustment and angularity of said guiding and holding means relative to the noses of the quills whereby to maintain the center of the twist 10 on the center line of the quills and also maintain the bisector of the angle defined by the shed wires extending back from said twist on the center line of the respective quills, said supports comprising a base adjustable in the direction of the length of 15 the fabric, a pivotal support on said base, a link pivoted on said pivotal support at one end and supporting said guiding and holding means on the other end thereof for arcuate adjustment thereabout.

28. In a weaving head for a wire cloth weaving machine having a row of closely adjacent quills geared together for simultaneous rotation the improved arrangement of rack drive therefor which comprises providing each quill with a gear tooth 25 periphery, the gear teeth of one quill being staggered relative to the teeth of its adjacent quill but overlapping the same, a complementarily toothed rack bar for driving said geared quills, said rack bar being operable in a path defining 30 a rectangle to thus drive said quills in a constant direction by maintaining constant mesh with alternate quills thus eliminating any lost motion or release of driving contact and means for imparting said motion to said rack. 35

29. In a weaving head for a wire fabric weaving machine having a row of closely adjacent quills geared together for simultaneous rotation adjacent quills being rotated in opposite directions, the improved arrangement of rack drive for said 40 quills comprising the gear teeth on adjacent quills being staggered and overlapped to form a first and second set, a toothed rack arranged to engage first one set of said geared quills and then the other set of said quills by shifting said rack 45 lengthwise of said teeth on said quills, said rack bar being operable in a path defining a rectangle to drive said quills in the same direction maintaining constant mesh with said alternate quills, thus eliminating any lost motion or release of 50 driving contact and means for imparting said motion to said rack.

30. In a weaving head for a wire fabric weaving machine having a row of closely adjacent quills geared together for simultaneous rotation of adjacent quills in the opposite direction, the improved arrangement of drive for said quills which comprises forming the gear teeth on adjacent quills in a staggered over-lapping relation to define a first and second set of alternate quills, a rack 65 for driving said geared quills, said rack being arranged for movement in a generally rectangular path engaging first one set of alternate quill gears to effect a 360° rotation thereof and then shiftable longitudinally of said teeth into engagement with 70 the gear teeth of the other set of alternate quills for driving the same through an arcuate movement of 360° in the same direction by shifting the rack in the opposite direction to the first named driving shift, said rack being moved back 75 into engagement with said first set of alternate quills by again moving the same lengthwise of said teeth, said arrangement being further particularly characterized by the fact that the spacing between the teeth on said rack is less than 75

the spacing of the teeth on said quill gears whereby to facilitate said shift lengthwise of said teeth from one set of plural gears to the other.

31. In a machine for weaving metal fabric, a quill for feeding a pair of warp strands, said quill being particularly characterized by the provision of a wedge-shaped forward nose portion adapted to facilitate its entry into a grooved backplate of a weaving head assembly, a pair of generally coaxial guides formed in said quill and intersecting said wedge-shaped nose at diametrically disposed points in the area of the extreme ends of said nose portion for feeding said pair of warp strands and effecting movement thereof in opposite directions relative to the median plane of the fabric.

32. In a machine for weaving metal fabric, a quill for feeding a pair of warp strands, said quill being particularly characterized by the provision of a pair of channel guides formed in the outer periphery of said quill and extending in a generally coaxial direction therealong to two diametrically disposed points of departure from the end of said quill, a toothed gear about the intermediate periphery of said quill for effecting the rotation of said quill, said generally coaxial guide lying in part in troughs between pairs of oppositely disposed teeth of said toothed gear.

33. In a machine for weaving metal fabric wherein a plurality of quills for feeding pairs of warp strands are geared together for simultaneous rotation, said quills being particularly characterized by the provision of wedge-shaped forward nose portions, each of said portions adapted to facilitate the entry of the ends of said quills into a grooved backplate of a weaving head assembly, a pair of generally coaxial guides formed in the outer periphery of each of said quills and passing along troughs between two substantially diametrically disposed pairs of quill gear teeth, said wedges being synchronously rotated, said guideways being brought out from said troughs to diametrically disposed points adjacent the ends of said wedge noses by curving the guideways on the quills, whereby the diameters between the said points on the respective quills are maintained parallel to each other.

34. In a metal fabric weaving machine including a plurality of rotatable quills for feeding a plurality of pairs of warp strands, the improved arrangement of supply means for supplying said warp wires to said quills comprising a plurality of tables rotatably geared together and corresponding in number to the number of pairs of warp wires, a pair of freely and independently rotatable spools of warp wire mounted on each of said tables, guide means for conducting said pairs of warp wires to the rear end of said respective quills and means for driving said tables in synchronism with the rotation of said quills whereby to prevent the twisting together of said warp wires behind said quills.

35. In a metal fabric weaving machine including a plurality of rotatable quills for feeding a plurality of pairs of warp strands, the improved arrangement of means for supplying said warp wires to said quills comprising, a plurality of tables rotatably geared together and corresponding in number to the number of pairs of warp wires, the axes of rotation of said tables being parallel and extending in the direction of the cloth, a pair of freely and independently rotatable spools of warp wire mounted on each of said tables, the axes of said spools being perpendicular to the axes of said tables, means for conducting

said pairs of warp wires to the rear ends of said respective quills and means for driving said tables in synchronism with the rotation of said quills, whereby to prevent the twisting together of said warp wires behind said quills.

36. In a metal fabric weaving machine including a row of rotatable quills for feeding a plurality of pairs of warp strands, a source of warp strand supply and guide means for conducting said pairs of warp wires to the rear ends of said quills, comprising a plurality of conduits through which each of said pairs of warp wires are guided, the forward ends of said conduits being connected to the rear ends of their corresponding quills by means of a universal joint.

37. In a metal fabric weaving machine including a row of rotatable quills for feeding a plurality of pairs of warp strands, a source of warp strand supply and guide means for conducting said pairs of warp wires to the rear ends of said quills comprising a plurality of enclosing conduits through which each of said pairs of warp wires are guided, the rear ends of said conduits being mounted in an antifriction bearing and the front ends thereof being connected with the rear ends of their respective quills through the medium of a universal joint.

38. In a metal fabric weaving machine including a row of rotatable quills for feeding a plurality of pairs of warp strands, a source of warp strand supply and guide means for conducting said pairs of warp strands to the rear ends of said quills comprising a plurality of conduits through which each of said pairs of warp strands are guided, the forward ends of each of said conduits being connected to the rear end of their corresponding quills by means of a universal joint, said universal joints comprising two resilient steel wires, the forward ends of which are inserted at diametrically disposed points in the rear ends of said quills and the rear ends of which are received within the forward ends of said conduits for supporting the same, said warp wires being fed through the forward ends of said conduits to the rear of said quills from discharge points disposed substantially on a second diameter normal to said first diameter.

39. In a metal fabric weaving machine including a row of rotatable quills for feeding a plurality of pairs of warp strands, a source of warp strand supply and guide means for conducting said pairs of warp wires to the rear ends of said quills comprising a first plurality of flexible conduits, one for each of said warp wires, through which the same are conducted from said supply to a point removed from the rear of said quills, a second conduit having the ends of said first conduits extended therein and supporting said second conduit, the forward portion of said second conduit converging to a reduced diameter and extending to a point more closely adjacent the rear end of said quills and being connected thereto by a pair of diametrically disposed resilient steel wires, the forward ends of which are inserted in the rear ends of said quills and the rear ends of said wires being received within said reduced forward end of said second conduit and supporting the same, a third pair of conduits received within said second conduit and extending from the forward end thereof to a point adjacent the ends of said first named conduit, said third set of conduits being substantially on a diameter located at right angles to said diameter on which the resilient steel connecting wires are positioned, said resilient steel wires acting as universal joint.

40. In a metal fabric weaving machine wherein quills are employed to feed warp strands, the improvement which comprises said quills being formed with a guideway therein for said warp strands, and resilient means carried by said quills in contact with said warp strands effective to urge the same against said guideway for placing said warp strand under a predetermined tension.
- 0 41. In a metal fabric weaving machine wherein quills are employed to feed warp strands, the improvement which comprises said quills being formed with a guideway therein for said warp strands, said guideway being sufficiently shallow so as not to completely receive said warp wire 5 therein, and resilient means carried by said quill in contact with said warp wire effective to urge the same against said guideway for placing said warp wire under a predetermined tension.

WALKLEY B. EWING. 10
